UNITED STATES PATENT OFFICE

GROVER B. HIGGINS, OF CHICAGO, ILLINOIS

COILING DEVICE

Application filed February 5, 1930. Serial No. 426,180.

The present invention relates to coiling devices, and is particularly concerned with coiling devices adapted to be used with electric extension cords for electric appliances or 5 telephones, or connecting any electric device to a source of supply.

The invention is of particular importance when used in connection with movable electric devices which require an extension cord 10 for the supply of electric current, or for the connection with other apparatus, but some of the features of the invention are of general application and may be used wherever it is desired to take up the slack and twist in 15 a cord, automatically.

The cord coiling devices of the prior art are best adapted to be used with an overhead supply socket or an elevated socket so that the coiling device is located in position to pay 20 out the cord to an electric appliance which is located below the point of attachment of the cord.

Where such a coiling device is used on a cord that is connected to a low socket, the 25 wire of the coiling device is apt to be pulled across the edge of the table, desk or other work support, catching on the corners in such manner as to constitute an annoyance and also marring the furniture through the 30 scratching of the coils of wire on the table, etc.

One of the objects of the invention is the provision of an improved arrangement for a coiling device adapted to be used with sockets in any location, and adapted to maintain 35 the coiling device and extension cord in the position which has the best operating characteristics.

Another object is the provision of an improved coiling device which eliminates entirely any twisting of the extension cord in 40 any position of the coiling device.

Another object is the provision of an improved coiling device of simple and effective design, having improved operating characteristics with respect to the maintenance of 45 the cord in the coiling device.

Another object is the provision of an improved bracket for coiling devices of the 50 class described, which is adapted to be con-

veniently clamped upon a work support to hold the coiling device in the most desirable position without further adjustment than the actual placing of the bracket in the clamped position.

Another object is the provision of improved devices of the class described, which are capable of long and efficient service, and which may be economically manufactured and assembled at a cost which is within the 55 means of a vast number of purchasers.

Another object is the provision of devices of the class described, which may be installed upon existing extension cords, telephone leads, etc. without detaching the electric 60 plugs, appliances or other devices at either end of the cord or lead.

Other objects and advantages of the invention will be apparent from the following description and from the accompanying drawings, in which similar characters of reference indicate similar parts throughout the 65 several views.

Referring to the drawings, of which there are two sheets;

Fig. 1 is a view in perspective of one embodiment of the present coiling device, showing its use in connection with an electric iron and ironing board;

Fig. 2 is a transverse sectional view taken on the plane of the line 2-2 of Fig. 4, showing the details of construction of the preferred form of bracket which may be used in the combination of Fig. 1;

Fig. 3 is a sectional view taken on the plane of the line 3-3 of Fig. 2;

Fig. 4 is an elevational view of the bracket in Fig. 2, taken from the right;

Fig. 5 is an end view of one of the convolutions of the improved form of coiling device;

Fig. 6 is a view in perspective of a part of an improved coiling device which eliminates entirely twisting of the wire at either end of the coiling device;

Fig. 7 is a detail view showing the connection between the coiling device and its supporting bracket.

Referring to Fig. 1, this is an installation which is exemplary of one of the preferred 100

forms of the invention, and while the present installation shows the use of an electric iron on an ironing board, it should be understood that the same arrangement is applicable to numerous other electrical devices and other types of work supports, such as tables, desks, shelves, etc.

In this arrangement, the ironing board or work support 10 is to be used in connection with the electric iron 11 which is supplied with current from a wall socket 12 located below the plane of the ironing board, and if the ordinary coiling device arrangement were used upon the extension cord 13, it will be evident that the respective coils of the coiling device 14 would have to slide over the edge of the ironing board as the coils are extended.

In order to eliminate the objectionable catching of the coils on the edge of the ironing board and to support the coiling device 14 in the most desirable operative position, I prefer to provide the coiling device 14 with a supporting bracket indicated in its entirety at 15, the bracket being preferably connected to the coiling device by means of a link 16. The bracket illustrated in Fig. 1 is one of the most simple types which may be most economically manufactured, and this bracket 20 may consist of an upwardly extending arm 17 which is provided with an aperture 18 at its upper end for receiving the link 16.

The upper end of the bracket 17 is preferably provided with a curved surface 19 for slidably engaging the inside of the link 16 and permitting the link 16 to shift from one side to the other of the bracket, thereby giving the link 16 a limited universal movement.

This movement is desirable for the reason that many of the coiling devices are so constructed that they must twist or uncoil slightly when the coils are extended, and the specific arrangement of the link 16 is capable 40 of permitting movement of the coiling device and extension of the coils without wear upon the cord or the wires of the coiling device. The link 16 may be hooked underneath one of the wires of the coiling device 14 before 50 the wire is applied to the cord 13.

The lower end of the bracket 15 is provided with a U-shaped formation 20, the upper leg of which is adapted to engage the top of the table or other part to which it is clamped, 55 and the lower side of which is provided with a clamping screw 21, so that the coiling device 14 may be quickly clamped to the ironing board 10 to hold the coils free from engagement with the board. The coiling device 14 is thus supported in the position which gives it the best operating characteristics, and as the iron 11 is moved back and forth, the coiling device 14 takes up the slack in the extension cord 13 and prevents interference of 65 the extension cord with the work.

Referring to Figs. 3 and 4, these are detailed views of a preferred form of the coiling device bracket which may be substituted for the bracket 15 in Fig. 1, and the bracket of Fig. 2 is peculiarly adapted to hold the coiling device in a number of different adjusted positions to suit the convenience of the operator.

The coil supporting arm 22 of this bracket preferably comprises a tubular metal member having an open slot 23 extending down its rear side in order to facilitate the insertion of the extension cord 13. If desired, the coiling device 14 may be secured to this arm in a manner similar to that previously described, but a peculiarly simple and effective form of connection between the tube 22 and the coiling device 14 may be provided by forming a narrow slot 24 in the top of the tube 22, the slot 24 being of sufficient width to receive the wire 14, but too narrow to pass a small knob 25 which is customarily formed on the end of the coiling device 14. If desired, a larger hook may be formed on the coiling device to perform the function of knob 25.

The extension cord 13 may also hang down outside of the tube 22 if desired, but in the preferred form of installation, this extension cord preferably enters the tube 22 adjacent its lower end through a rubber bushing 26, and the cord 13 extends upward through the tube 22 and out of a rubber bushing 27. Both of the bushings 26 and 27 may be split longitudinally so that the rubber may be spread apart to permit the extension cord 13 to be located in the bores 28, 29 of the bushings. When the bushings are located in assembled relation with the tube 22, they grip the extension cord and hold it in the tube 22 so that the cord is protected against any injury and the coil supporting arm 22 of the bracket provides a support for the coiling device as well as a conduit for enclosing and concealing a part of the extension cord.

The lower end of tube 22 is preferably secured to a ball 30 having a shank 31 which is fastened in the tube 22 by a pin 32 or by threading the shank 31 into the tube. The ball 30 is preferably supported for a limited universal movement by a sheet metal bracket 33 having a socket 34 stamped therein and provided with an enlarged aperture 35 giving considerable clearance about the shank 31. The socket 34 is shallower than the diameter of the ball 30, so that when the ball 30 is located in socket 34, the ball projects slightly from the socket and is adapted to engage the ironing board 10 or other work support to which the bracket 33 is clamped.

It will thus be observed that when the bracket 33 is clamped on ironing board 10, the ball 30 will be clamped in a certain adjusted position which may be readily determined by the operator when the bracket 33 is located on the ironing board.

The bracket 33 is also preferably provided with a clamping member 36 which may consist of a sheet metal member having a downwardly turned tongue 37 which is adapted to be engaged by the coils of one end of a spring 38. The clamping member 36 also has a downwardly projecting flange 39 having a threaded bore 40 for receiving a thumb screw 41.

10 The bracket 33 is also provided with a slot 42 for receiving the body of the thumb screw 41 and the slot 42 may be formed by cutting out a portion 43 from the body of the bracket 33, the portion 43 being bent at 15 right angles to the body 44 of the bracket to form a handle. The lower end 45 of the bracket 33 may also extend horizontally and may be provided with an upwardly projecting tongue 46 adapted to be engaged by the 20 coils at the lower end of the spring 38, and the spring 38 is thus confined between the end 45 of the bracket and the clamping member 36. The spring 38 thus urges the clamping member 36 into clamping position, but 25 the clamping member 36 may be moved downward away from the ball 30 by pressing the thumb screw 41 and the handle 43 between the thumb and fingers of one hand, and the clamping member 36 is slidably supported on the bracket 13 in such manner that 30 the bracket may be secured in clamping position by merely pressing upon the thumb screw 41 and the handle 43 while the bracket is located on the ironing board.

35 When the bracket is clamped in the position shown in Fig. 2, the ball 30 engages the top of the ironing board and the coil supporting arm 22 is automatically secured in any one of a plurality of different adjustable positions.

Under some conditions, it may be more desirable to have the coil supporting arm 22 lean over towards the side of the ironing board so that the coiling device 14 is entirely 45 out of the way. Under other conditions, it may be desirable to give the coiling device more slack by inclining the arm 22 towards the electric appliance or iron 11, but in any event, the arm may be very quickly secured 50 in the desired position by merely clamping the bracket on the table or board.

Since considerable pull might be exerted upon the coil supporting bracket under some conditions, it may be desirable to give the thumb screw 41 a turn to secure the clamping element more firmly in the desired position, but even under such conditions, the spring 38 is of great assistance in facilitating the location of the bracket because the spring 38 automatically holds the clamping member 36 in the desired clamping position, while the operator is adjusting the thumb screw 31. Additional pressure may be placed 55 on the ironing board 10 by the use of another

thumb screw 47 passing through the clamping member 36.

Referring to Fig. 5, I have here illustrated an end view of one of the preferred improved forms of a coiling device which may be used in the present coiling arrangement. It should be understood that any of the coiling devices of the prior art may be utilized as shown in Fig. 1 or with the improved bracket of Fig. 2, but the coiling device illustrated in Fig. 5 is an improved form which has more desirable operating characteristics with respect to the maintenance of the extension cord 13 in the coiling device.

80 The coiling device 14 is preferably provided with a plurality of oppositely disposed or oppositely extending clamping formations 48, 49, and these formations may consist of a plurality of substantially U-shaped loops 85 formed in the wire 14 of the coiling device.

Since the clamping formations 48, 49 are oppositely disposed, the wire portions 50 between the loops 48, 49 extend substantially in a diagonal direction across the extension cord 13, and the complete coiling device 14 consists of an elongated wire preferably formed of tempered steel or other tough resilient material which is provided alternately with a loop 48 extending inward, a diagonal portion 50, a loop 49 extending outward, etc.

90 For clarity of illustration in Fig. 5, the loops 48 and 49 are shown extending substantially radially of the coils of the extension cord 13, but it should be understood that it is immaterial which direction these loops extend, so long as they are oppositely disposed to each other. Thus, in Fig. 5, the loop 48 confines the extension cord on one side of the adjacent loops 49, confining the extension cord on the other side. Any force which would tend to pull the extension cord out of one loop would at the same time tend to pull the cord into the adjacent oppositely disposed loops, and on account of this particular arrangement, the present coiling device is 95 peculiarly adapted to keep the extension cord in proper position within the loops 48, 49.

100 The wire 14 of the coiling device also extends in the general direction of a helix so as to hold the extension cord 13 in coils as shown in Fig. 1 or Fig. 6. It should also be understood that the same arrangement may be utilized with other forms of devices for taking up slack, and the helical convolutions 110 are only one of the many forms which the device may take.

115 Referring to Fig. 6, the particular arrangement of the coiling device illustrated in this figure is peculiarly adapted to take up and pay out slack in a cord without any twisting of the cord at the ends of the coiling device. For this purpose, the coiling device 14 consists of a wire having the clamping formations 48 or 49 and extending in the general 120

130

direction of a left hand helix over a certain portion of the coils as at 51. At the point 52 the direction of the coils of the helix is reversed, and for the remainder of the coiling device the wire 14 extends in the general direction of a right hand helix from the point 52 onward as at 53.

When an ordinary helical coiling device is subjected to a pull on the extension cord 13, 10 the respective coils separate and pay out slack, but at the same time a certain amount of uncoiling inevitably takes place, and this produces some twisting of the extension cord at the ends of the coiling device. However, 15 in the device of Fig. 6, any twisting of the respective right hand and left hand helices 51, 53, is taken up by rotation of the juncture 52 between the helices, and there is no twisting at the ends of the coiling devices.

It will thus be observed that I have invented an improved arrangement for coiling devices, by means of which the coiling device may be located in the most desirable operating position, including an improved form of 20 wire for the coiling device which is peculiarly adapted to maintain the cord in firm engagement with the wire, and a particular form of convolution for the coiling device which eliminates twisting of the extension 25 cord at both ends of the device.

Since all of the convolutions of the coiling device in Fig. 6 will be substantially identical, only one turn each of the right hand and left hand helices have been shown in 30 full, and it will be understood that as many convolutions may be utilized as may seem desirable in any particular situation. The convolutions are illustrated in extended position.

The improved form of coil supporting 40 bracket also is peculiarly adapted to support the coiling device in the most convenient positions, and the bracket may be secured in any of a plurality of adjustable positions by 45 merely placing the bracket upon the edge of a table or other work support.

When the present arrangement is used with 50 a coiling device, there is no possibility of the coils catching on the edge of a table or other work support, and the coiling devices may 55 be utilized with low sockets which would otherwise render the use of a coiling device practically impossible. When the coiling devices of the prior art are improperly installed in such manner as to interfere with 60 the table, desk or other furniture, they may mar the furniture and become a source of constant annoyance, and the arrangement of the present invention is adapted to eliminate such difficulties.

While I have illustrated a preferred embodiment of my invention, many modifications may be made without departing from the spirit of the invention, and I do not wish 65 to be limited to the precise details of con-

struction set forth, but desire to avail myself of all changes within the scope of the appended claims.

Having thus described my invention, what I claim is new and desire to secure by Letters Patent of the United States, is:

1. A coiling device for electric extension cords, comprising a resilient metal wire member, having the general shape of a helix and adapted to support the extension cord in helical form to take up slack in said cord, and a multiplicity of clamping loops formed in said wire and adapted to secure said extension cord to said wire, said loops having open sides disposed oppositely with respect to adjacent loops, to facilitate insertion of said cord in said loops and confine said cord at opposite sides of said cord. 75

2. A coiling device for electric extension cords, comprising a resilient metal wire member, having the general shape of a helix and adapted to support the extension cord in helical form, said wire member being formed with a plurality of open-sided loops to facilitate insertion of said cord in said loops, said loops having their open sides oppositely disposed with respect to adjacent loops, and diagonally extending, substantially straight portions of wire joining said loops and extending longitudinally of said extension cord. 90

In witness whereof, I hereunto subscribe my name this 31st day of January, 1930.

GROVER B. HIGGINS.
